UNITED STATES PATENT OFFICE.

ISAAC H. LEITER, OF NEW YORK, N. Y.

DESIGN FOR GIMP.

SPECIFICATION forming part of Design No. 16,918, dated September 28, 1886.

Application filed June 4, 1886. Serial No. 204,179. Term of patent 14 years.

To all whom it may concern:

Be it known that I, ISAAC H. LEITER, a citizen of the United States, residing in the city, county and State of New York, have invented and produced a new and original Design for Gimps, of which the following is a specification, reference being had to the accompanying drawing, forming part thereof.

My new design for gimps consists of a configuration formed of a longitudinal band of any desired width running along the center of the gimp, transverse bars running at desired intervals across and over the same less than the space covered by the longitudinal strands 15 of chenille referred to herein, and a longitudinal strand of chenille of any desired size covering each edge of the face of the gimp and being divided into sections by transverse bars running across and over the same at desired intervals.

The drawing represents a face view of my new design.

A represents the central band; B, the transverse bars crossing the central band; C C, the longitudinal strands of chenille, and D the 25 transverse bars crossing the strands of chenille.

I claim—

The new design for gimps, which consists of the central longitudinal band A, transverse bars B, crossing the same at desired intervals 30 less than the space covered by the longitudinal strands C C, covering each edge of the face of the gimp, and transverse bars D, crossing said strands, substantially as shown and described.

I. H. LEITER.
